US00D960101S

(12) **United States Design Patent** (10) **Patent No.:** **US D960,101 S**
(45) **Date of Patent:** **** Aug. 9, 2022**

(54) **SOCKET**

(71) Applicant: **Dongguan Wontravel Electric Co., Ltd., Guangdong (CN)**

(72) Inventor: **Liangguan Lin, Guangdong (CN)**

(**) Term: **15 Years**

(21) Appl. No.: **29/763,526**

(22) Filed: **Dec. 23, 2020**

(51) LOC (13) Cl. **13-03**

(52) U.S. Cl.

USPC **D13/139.8**

(58) **Field of Classification Search**

USPC D13/137.1, 137.2, 137.3, 137.4, 138.1, D13/138.2, 139.1, 139.2, 139.3, 139.4,

(57) **CLAIM**

The ornamental design for a socket, as shown.

DESCRIPTION

FIG. 1 is a front elevational view of a socket showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof; and,

FIG. 9 is a third perspective view thereof.

1 Claim, 8 Drawing Sheets
